UNITED STATES PATENT OFFICE.

MICHAEL A. DUNN, OF POUGHKEEPSIE, NEW YORK.

CLEANER FOR TUMBLERS FOR METAL CASTINGS, BUTTONS, AND OTHER ARTICLES.

1,211,111.

Specification of Letters Patent.

Patented Jan. 2, 1917.

Application filed March 1, 1916. Serial No. 81,367.

To all whom it may concern:

Be it known that I, MICHAEL A. DUNN, a citizen of the United States, and a resident of Poughkeepsie, in the county of Dutchess 5 and State of New York, have invented a new and Improved Cleaner for Tumblers for Metal Castings, Buttons, and Other Articles, of which the following is a full, clear, and exact description.

10 Among the principal objects which the present invention has in view are: to prevent accumulation of deposit of scale, grit, or other debris, in the separating chambers provided in tumblers of conventional form; to 15 separate dust or light pulverulent matter from the deposit mentioned; to avoid the necessity inherent in tumblers of conventional construction for discontinuing the service thereof during periods when the 20 debris has accumulated in the separation chamber; and to maintain at all times a free circulation of air through the tumbler.

Drawings.—Figure 1 is a sectional elevation of a tumbler of conventional form, 25 showing employed therewith a cleaner constructed and arranged in accordance with the present invention; Fig. 2 is a cross section taken as on the line 2—2 in Fig. 1; Fig. 3 is a cross section of the dust-separating chamber employed in the present invention.

Description.—As shown in the drawings, a tumbler of conventional form is provided with a cylindrical body 8. The body 8 has 35 fitted thereto and at both ends thereof, screens 9. As best shown in Fig. 2 of the drawings, the screens 9 are provided with perforations 10, through which small bits of scale, grit, or dust are carried from the portion of the body where usually castings are 40 bolted or held. The body 8 is furnished with a closure section or door 11, which when opened permits access to the interior of the body. The body 8 is mounted in 45 heads 12, each having a flange 13, which encloses the body 8, as seen best in Fig. 1 of the drawings. Integrally formed with the heads 12, are tubular shafts 14, which have bearings in standards 15. Through the 50 shafts 14 and the body 8, air is continuously circulated, and in the direction shown by the arrows *a* in Fig. 1 of the drawings. Any suitable draft-impelling mechanism is employed for this purpose. One of the shafts 55 14 opens into the dust-separating chamber 16. The dust-separating chamber has a bolt-

ing flange 17, by which it is stationarily mounted on an adjacent standard 15. From the upper end of the chamber is extended a delivery pipe 18. The pipe 18 conveys dust-laden air to any suitable depository where, if desired, the dust is separated from the air by any of the well-known and approved methods of cleansing the air. At the lower end of the separating chamber 16, a trap 60 door 19 closes the chamber and prevents the debris 20, which accumulates in the chamber, falling on the ground or floor while the receptacle in which the debris is removed, is carried to the dump. The free end 21 of 65 the door may be weighted or locked down to prevent the opening of the door except when moved by an attendant. The door 19 is pivotally mounted by a hinge pin 22 on the lower end of the cylinder having the chamber 16. Bolted to the inner wall of the chamber 16, is a chute 23. The chute 23 is guttered and extends at the receiving end thereof, close to the face of the screen 9 adjacent the chamber 16. The receiving end 70 of the chute 23 is, as shown best in Fig. 1 of the drawings, raised above the delivery end thereof. The delivery end of the said chute has a delivery opening 24 situated within the chamber 16. 75

It will be understood that when installing or removing the cleaner herein described, the bolts 25 are withdrawn from the flange 17, when the cylinder having the chamber 16 may be removed from service position, the 80 chute 23 being guided through the opening of the shaft 14. If necessary, the union 26 by which the pipe 18 is connected with the chamber 16, is released. 85

Operation.—When the cleaner is installed 90 as shown in the accompanying drawings, and as described above, the operation is as follows: The door 11 is removed or thrown back, as the case may be, and the body 8 of the tumbler is suitably packed with castings 95 to be cleaned. If the cylinder is not loaded with the usual charge of "stars", or other small bits of hardened metal, this is done prior to replacing the door 11. The door 11 having been replaced, the tumbler is rotated 100 by furnishing power to the pulley 28, a belt 29 being employed to this end. Air is now turned on to produce a current through the hollow shafts 14, the body 8 and chamber 16. Any suitable means for supplying this air 105 is employed. The object is to remove the dust extracted from the castings by the 110

stars, and to avoid the interior of the body 8 becoming fouled therewith. A further object is to convey over the small particles of grit or scale, which are removed from the 5 castings by the attrition of the stars 27. All pulverulent matter, it will be understood, if retained in the body 8, will be reduced by the attrition of the stars 27, into a powdered or dust condition, when it will be carried 10 through the screen 9 at the far end of the body 8 to the chamber formed by the said screen and the head 12 at this end.

In common practice it is found that the 15 grit which is light enough to be carried 15 from the interior of the tumbler body 8, is arrested by the walls of the head 12, and failing of suspension, drops to the bottom or outer edge of the head, where the same joins the screen 9. In time this fills, so that the 20 perforations 10 in the screen 9 become clogged and the cleansing power of the current of air is dissipated or completely obstructed. When employing the present invention, however, the debris thus accumulated 25 is carried by the rotation of the head 12 and body 8, above the receiving end of the chute 23, and in dropping, part of the debris falls into the said chute down which it is carried to the delivery opening 24, and 30 from thence to the bottom of the chamber 16 to rest on the door 19. While the debris is constantly accumulating, also the chute is constantly operating, with the net result that the accumulation in the bottom of the 35 head 12 is minimized, if not totally obliterated. The dust held in suspension by the current of air, passes, as in the conventional construction, through the shaft 14, at the delivery end of the body of the tumbler, and 40 from the chamber 16 to the delivery pipe 18. The upward lift of the current of air in the chamber 16 facilitates the separation from the current of air, of particles too heavy for natural suspension, which particles if carried over might clog the pipe 18. These particles are permitted, within the 45 compass of the chamber 16, to settle until passing out of the direct influence of the current of air, they fall to the bottom of the chamber 16, from whence they are removed whenever the load on the door 19 becomes 50 sufficiently great to open the said door or when the attendant operates the door with this purpose in view. At the end of the operation, the door 11 is opened and the castings from which the scale and grit have 55 been removed are withdrawn from the tumbler. When provided with a cleaner such as described, it is obvious that the body 8 may 60 be operated continuously without requiring

the removal of the head 12 to liberate the accumulation of debris therein.

Claims:

1. A tumbler having a tubular end journal and an end chamber separated from the body of said tumbler by a screen; in combination with a cleaner comprising a receptacle in open communication with said chamber; means for discharging the solids collected in said receptacle; means for delivering air-suspended particles from the tumbler to the receptacle; means for discharging the dust or air-suspended articles from said receptacle; and an inclined chute rigidly mounted in said receptacle and having a receiving end extending into the adjacent chamber of said tumbler in the path of debris when dropped from the upper side of said chamber when carried there by the rotation of said tumbler. 80

2. A tumbler having a tubular end journal and a collecting chamber formed adjacent said journal; in combination with an inclined chute stationarily supported and extending into the adjacent collecting chamber, and adapted to receive the debris carried by the rotation of said tumbler above the axis of the same; a receptacle for said debris, said receptacle being in open communication with the collecting chamber 90 through the journal, the chute extending through but not closing said journal, and terminating within the receptacle, said receptacle being adapted to separate the lighter from the heavier particles delivered 95 from the tumbler.

3. A tumbler having a tubular end journal; in combination with a cleaner for removing debris from said tumbler, said cleaner comprising a receptacle in open communication with said journal; means for discharging the solids collected in said receptacle, there being an air-delivery opening at the upper end of said receptacle; and an inclined chute rigidly mounted in said receptacle and having a receiving end extending through said journal into the adjacent end of the tumbler in the path of debris accumulated in said end when carried to the upper side by the rotation of said tumbler, 100 said chute being of such dimension as to only partially obstruct the communication through the journal. 105

In testimony whereof I have signed my name to this specification in the presence of 115 two subscribing witnesses.

MICHAEL A. DUNN.
